UNITED STATES PATENT OFFICE.

JOHN G. BARTELL, OF ST. PAUL, MINNESOTA.

SWINGING SCAFFOLD

1,183,520.

Specification of Letters Patent. Patented May 16, 1916.

Application filed February 13, 1915. Serial No. 7,947.

To all whom it may concern:

Be it known that I, JOHN G. BARTELL, a citizen of the United States, residing at St. Paul, in the county of Ramsey and State 5 of Minnesota, have invented new and useful Improvements in Swinging Scaffolds, of which the following is a specification.

My invention relates to improvements in swinging scaffolds.

10 The common form of adjustable scaffold includes a platform suspended from outriggers by cables arranged at intervals along the length of said platform and a plurality of independently operated winding drums 15 or other devices, mounted above the platform and attached severally to the cables. In elevating such scaffolds a strong operator is required at each drum. Said drums obstruct the laborers in their work upon said 20 scaffold and are unprotected against accidental blows, such as those delivered by workmen or falling objects.

It is the object of my invention to provide a simple and durable scaffold, consisting of 25 a working platform resting upon a series of supports, each support being carried by a pair of cables and having improved operating mechanism easily manipulated by a single attendant to raise or lower the scaffold 30 on its supporting cables.

A further object is to provide a device of this kind constructed with the operating mechanism thereof beneath the working platform to permit unobstructed access to 35 the work from said platform and to guard said mechanism against injury from above.

In the drawings Figure 1 is a side elevation of my improved scaffold; Fig. 2 is a transverse sectional view in detail taken on 40 the line 2-2 of Fig. 3, and illustrates one of the platform supports, and Fig. 3 is a longitudinal sectional view in detail taken on the line 3-3 of Fig. 2.

Referring to the drawings, I have used 45 the reference letter A to indicate the supporting cables; B the platform, and C the adjustable supports on which said platform rests.

The cables A are suspended in pairs from 50 out-riggers upon a building, each pair being attached to a support C, which is carried thereby in horizontal position with the inner end of said support adjacent to the wall of the building in course of erection.

55 The platform B is built of boards or planks and are of a length to overlap three

supports. These planks rest upon and are loosely bolted to beams 10 (hereinafter described) of the supports C, and may be laid in staggered relation or otherwise, as desired. 60

Each support C is constructed as follows: A pair of parallel supporting beams 10, preferably angle irons, are rigidly joined by a plurality of hangers 11. A drum shaft 12, 65 square in cross-section, carries two drums 13 and is supplied with journals 14, which turn in bearings 15 in said brackets. Said drum shaft is furnished with a large driving gear 16 and with two ratchet wheels 17, the teeth of one ratchet wheel resting in staggered relation with respect to the teeth of the other ratchet wheel. A countershaft 18, 70 revolvably mounted in two of the brackets 11 is provided with a toothed wheel 19, meshing 75 with the driving gear 16, and with a ratchet wheel 20. A bifurcated arm 21 pivoted on said countershaft straddles the ratchet wheel 20 and carries a dog 22, which engages said ratchet wheel by its own weight. A lever 23, 80 detachably secured to the arm 21, extends above the platform at the outer edge thereof, and is employed to rock said arm. During one stroke of the arm 21 the dog 22 engages the ratchet wheel 20 and operates 85 through said ratchet wheel, countershaft 18, gears 19 and 16 and drum shaft 12 to turn the drums 13 and wind upon each of said drums a length of cable, thus lifting the machine one step. A dog 24 pivoted on the 90 countershaft 18 engages one of the ratchet wheels 17 and a second dog 25 pivoted on one of the beams 10 engages the other ratchet wheel 17. Said dogs alternately engage said ratchets by their own weight and provide 95 safety devices to secure the drums against backward rotation, and thereby prevent the support and scaffold supported thereon from falling. A post socket 26 secured to the inner side of the outer hanger 11 is adapted to 100 receive a post 27, to which fence wires 28 and side rails 29 may be attached.

To protect the arm 21 when a machine is handled in shipment, I attach a guard 30 upon one of the beams 10. Said guard receives the end of the arm 21 when tilted to position shown in dotted lines in Fig. 2 and said arm is secured in position on said guard by the spring clip 31, which engages the upper side thereof. 105

In use cables A are hung in pairs from lookouts or out-riggers upon a building or 110

other structure. Each pair of cables is attached to a support by securing the free end of one cable to one drum and the free end of the other cable to the other drum. 5 The platform B is laid upon the beams 10 of the supports. Posts 27 are erected in the post sockets 26 and guard rails 29, wires 28 or the like secured thereto. The levers 23 are manipulated to turn the drums 13 and 10 raise the scaffold.

It will be noted that the operation of a single lever turns both of the winding drums on each support; that the power transmitting mechanism between the lever 23 and 15 drum shaft 12 provides for easily elevating a section of the scaffold; that the operating mechanism occupies none of the working space upon the scaffold, and that said mechanism is protected against injury and accident 20 displacement by the scaffolding.

It is obvious that independent drum shafts and operating devices for each drum may be provided without departing from the scope of my invention.

Having described my invention, what I 25

claim as new and desire to protect by Letters Patent is:

In a device of the class described, the combination with a plurality of out-riggers and a pair of cables suspended from each 30 out-rigger, of an adjustable support for each pair of cables, each support comprising a pair of spaced platform carrying beams, hangers joining said beams, a drum shaft revolvable in said hangers below said beams, 35 a pair of drums on said shaft, said cables passing between said beams and wound, one on each drum, means to turn said drum shaft and a platform comprising a plurality of abutting sections, the adjacent ends of said 40 sections resting upon separate carrying beams of a support.

In testimony whereof, I have signed my name to this specification in the presence of two subscribing witnesses.

JOHN G. BARTELL.
